BOAT HULL

Clair A. Huard, Detroit, Mich.

Application December 30, 1943, Serial No. 516,262

4 Claims. (Cl. 114—66.5)

This invention relates to improvements in hull construction for racing and other boats, and important objects of the invention are to provide a hull construction of this kind that is compact and durable in form, capable of attaining a very high speed of travel, and adapted to be turned or steered in either desired direction within a small radius at fairly high speed and with comparative safety.

More, particularly, the invention contemplates the provision of a boat hull construction including a flat-like, elongated body whose major portion is of a form and shape to constitute an efficient primary lifting plane or airfoil having a broad rounded nose and tapering narrower at the rear, with upper and lower surfaces suitably curved transversely and longitudinally to afford efficient lifting action when the boat is driven at high speed.

The invention further contemplates the provision of a boat hull of the above character whose central rear under surface portion constitutes a rear supporting plane or surface which affords the only contact of the body with the water when the boat is traveling at a very high speed, the area of such contact being relatively small to ensure minimum friction or resistance to forward travel.

Still further, the present invention contemplates the provision of a boat hull of the character mentioned above, and wherein the hull, near its forward portion, is provided in its under surface and at opposite sides with longitudinal elongated recesses that accommodate rocking balancing planes mounted upon parallel axes extending parallel with the longitudinal axis of the boat, and so designed and mounted as to act upon the air and/or water when the boat is sharply turned in either direction for preventing side slip and enabling the making of fairly short turns at relatively high speed with comparative safety.

Other objects and features of the present invention will become apparent from the following description when considered in connection with the accompanying drawings.

The invention consists in the novel form, combination and arrangement of parts hereinafter more fully described, shown in the accompanying drawings and claimed.

In the drawings, wherein like reference characters indicate corresponding parts throughout the several views:

Figure 1 is a bottom plan view of a racing boat constructed in accordance with the present invention.

Figure 2 is a side elevational view thereof.

Figure 3 is a front elevational view of the same, and

Figure 4 is a fragmentary longitudinal section taken on the plane of line 4—4 of Figure 1.

Referring in detail to the drawings, the present boat hull includes a flat-like body 5 whose major portion is so formed and shaped as to constitute an efficient primary lifting plane or airfoil having a broad rounded nose end 6 and having its rear portion tapered narrower, as at 7. As will be seen from an inspection of Figures 2 and 3, the upper surface of this lifting plane or airfoil is suitably curved longitudinally and transversely, and the major central portion of the lower surface is also longitudinally curved to afford an efficient lifting plane or airfoil. Preferably, the primary plane or airfoil tapers thinner toward the front and side edges, as at 8 and 9, and has a relatively long sloping rear upper surface portion, as at 10.

The body has a longitudinally elongated central rear under surface portion 11 that inclines slightly in a rearward direction and constitutes a rear supporting plane or surface of comparatively small area. When traveling ahead at very high speed, this is the only surface of the body that partially contacts the surface of the water, thereby ensuring minimum friction or resistance to forward travel and promoting the attainment of very high speeds. The body projects rearwardly of the rear supporting plane or surface 11 where it is tapered substantially to a point, as at 12.

The body has a compartment formed in the rear central portion thereof over which is erected a suitable superstructure 13 adapted to accommodate the pilot and to house the propeller driving motor and various necessary speed-controlling, steering and other devices. A tubular housing 14 projects through the bottom of the body centrally between the sides of the rear portion of the latter, and the drive shaft for the propeller of the boat is adapted to project through this housing, as generally indicated by dotted lines in Figure 2.

The invention further contemplates the provision of rocking forward balancing planes which act to prevent side slip when the boat is steered laterally in either direction, thereby enabling the negotiation of short turns at fairly high speeds with comparative safety. As shown, the body 5 is formed in opposite sides of its under surface and near its forward end with elongated longitudinal pockets or recesses 15 that accommodate the upper portions of similar rocking balancing planes 16 mounted upon longitudinal parallel axes at 17 parallel with each other and with the longitudinal axis of the body. Each balancing plane 16 consists of a hollow elongated member that tapers smaller in a forward direction, as shown in Figures 2 and 4, and that has a major transversely curved arcuate surface portion 18 and a V-shaped but nearly flat remaining surface portion 19. The balancing planes 16 are pivoted in brackets or hangers 20 attached to the body

and depending slightly below the lower surface of said body so that the planes 16 project below said under surface of the body as shown. The pivots 21 of the planes 16 are located adjacent and midway between the sides of the surface portion 19, which is at a point nearer the arcuate surface 18 than the center of the radius of said surface 18. In this way, the planes 16 are disposed so that they will contact the walls of the recesses 15 to limit rocking movement of said planes to substantially a quarter turn in either direction. In operation at fairly high speed, the balancing planes will be caused to automatically assume the dotted line position for the right hand plane 16 of Figure 3 when the boat is steered to the right, and the dotted position of the left hand plane 16 when the boat is steered to the left. Thus, flat surfaces are automatically presented to the wind or water for minimizing side slip when making turns, thereby facilitating short turns at such fairly high speed with comparative safety. Of course, when the boat is traveling at a very high speed, the balancing planes will be entirely out of the water and will be frictionally maintained in their full line position of Figure 3 by the pivots thereof. When lying on the water, the planes 16 naturally assume the full line positions of Figure 3.

From the foregoing description, it is believed that the behavior and functioning of the various features and elements will be readily apparent. It will be seen that I have provided a very compact and durable boat hull of the kind specified having provision for effectively carrying out the stated objects of the invention. Minor changes in form of parts and details of construction are contemplated, such as fairly fall within the spirit and scope of the invention as claimed.

What I claim as new is:

1. A boat hull comprising a very flat and broad elongated body whose major forward portion is formed and shaped to afford a primary lifting plane or airfoil having a comparatively blunt and broad rounded nose end and an upper surface which curves upwardly longitudinally and transversely and whose major central under surface portion is flat transversely and curves forwardly and upwardly at the forward end, the rear central under surface portion of the body affording an elongated rear supporting plane or surface inclined rearwardly, the rear portion of the primary lifting plane tapering narrower in a rearward direction and merging with the rear end of the body, said rear end of the body being tapered substantially to a point, the under surfaces of the portions of the body at opposite sides of said central under surface portions being inclined outwardly and upwardly.

2. A boat hull comprising a flat-like elongated body whose major forward portion is formed and shaped to afford a primary lifting plane or airfoil having a broad rounded nose end and an upper surface which curves upwardly longitudinally and transversely and whose major central under surface portion curves forwardly and upwardly at the forward end, the rear central under surface portion of the body affording an elongated rear supporting plane or surface inclined rearwardly, the rear portion of the primary lifting plane tapering narrower in a rearward direction and merging with the rear end of the

body, said rear end of the body being tapered substantially to a point, said body being provided in its under surface at opposite sides and near its forward end with longitudinal elongated recesses, and rocking balancing planes pivoted to the under side of the body and partially accommodated in said recesses, means pivotally mounting said balancing planes upon longitudinal axes parallel with the longitudinal axis of the boat so as to have limited rocking motion in either direction.

3. A boat hull comprising a flat-like elongated body whose major forward portion is formed and shaped to afford a primary lifting plane or airfoil having a broad rounded nose end and an upper surface which curves upwardly longitudinally and transversely and whose major central under surface portion curves forwardly and upwardly at the forward end, the rear central under surface portion of the body affording an elongated rear supporting plane or surface inclined rearwardly, the rear portion of the primary lifting plane tapering narrower in a rearward direction and merging with the rear end of the body, said rear end of the body being tapered substantially to a point, said body being provided in its under surface at opposite sides and near its forward end with longitudinal elongated recesses, and rocking balancing planes pivoted to the under side of the body and partially accommodated in said recesses, means pivotally mounting said balancing planes upon longitudinal axes parallel with the longitudinal axis of the boat so as to have limited rocking motion in either direction, each balancing plane having a major substantially semi-cylindrical surface portion and a remaining surface portion of V shape but nearly flat form.

4. A boat hull comprising a flat-like elongated body whose major forward portion is formed and shaped to afford a primary lifting plane or airfoil having a broad rounded nose end and an upper surface which curves upwardly longitudinally and transversely and whose major central under surface portion curves forwardly and upwardly at the forward end, the rear central under surface portion of the body affording an elongated rear supporting plane or surface inclined rearwardly, the rear portion of the primary lifting plane tapering narrower in a rearward direction and merging with the rear end of the body, said rear end of the body being tapered substantially to a point, said body being provided in its under surface at opposite sides and near its forward end with longitudinal elongated recesses, and rocking balancing planes pivoted to the under side of the body and partially accommodated in said recesses, means pivotally mounting said balancing planes upon longitudinal axes parallel with the longitudinal axis of the boat so as to have limited rocking motion in either direction, each balancing plane having a major substantially semi-cylindrical surface portion and a remaining surface portion of V shape but nearly flat form, the pivots of the balancing planes being located nearer to the semi-cylindrical surfaces thereof than the axes of said surfaces so that the planes coact with the recess walls to limit the rocking movement.

CLAIR A. HUARD.
